UNITED STATES PATENT OFFICE.

AXEL PERSON, OF ATTLEBORO, MASSACHUSETTS, ASSIGNOR TO HARVEY CLAP CO., OF ATTLEBORO, MASSACHUSETTS, A PARTNERSHIP.

CONSTRUCTION FOR WRIST-WATCH CHAINS AND THE LIKE.

Application filed December 22, 1923. Serial No. 682,148.

To all whom it may concern:

Be it known that I, AXEL PERSON, a citizen of the United States, and a resident of Attleboro, in the county of Bristol and 5 State of Massachusetts, have invented an Improvement in Construction for Wrist-Watch Chains and the like, of which the following is a specification.

This invention relates to construction for 10 wrist watch chains and the like, and with regard to certain more specific features to construction for such devices employing precious metals.

One of the objects of the invention is to 15 provide a construction of the above nature practical and efficient and capable of meeting the requirements of use in a highly satisfactory manner. Another object is to provide a construction of the above nature of a 20 strong and durable character. Another object is to provide a construction adapted, at all times, to present a neat and attractive appearance. Another object is to provide such a construction wherein precious metals 25 employed are most economically and advantageously utilized. Another object of this invention is to provide a wrist chain in which the expansion thereof, necessitated by the attachment of the chain to the wrist, may 30 be achieved without destroying its continuity of design. Other objects will be in part obvious or in part pointed out herein-after.

35 The invention accordingly consists in the features of construction, combinations of elements, and arrangements of parts, all as will be illustratively described herein, and the scope of the application of which will be 40 indicated in the following claims.

In the accompanying drawing in which is shown one of various possible embodiments of the several mechanical features of this invention,

45 Figure 1 is a top plan view of a portion of a wrist watch chain.

Figure 2 is a view similar to Figure 1 showing the parts in extended position.

50 Figure 3 is a bottom plan view in enlarged detail of the construction shown in Figures 1 and 2.

Figure 4 is a lateral longitudinal section.

Figure 5 is a vertical longitudinal section.

55 Figure 6 is a transverse section taken substantially along the line 6—6 of Figure 5.

Figure 7 is a transverse section taken substantially along the line 7—7 of Figure 3.

Figure 8 is an end elevation of the part shown in section in Figure 7, the part being shown at an early stage of its manufacture.

Figure 9 is a view similar to Figure 8 showing the same part at a later stage, and

Figure 10 is a plan view of Figure 9.

Similar reference characters refer to similar parts throughout the several views of the drawing.

Referring now to the drawing in detail, in Figure 1 there is shown, somewhat diagrammatically, a plan view of the end portion of a chain adapted for use in connection with a wrist watch or the like. The chain preferably comprises a plurality of blocks or bars indicated generally at 10 and joined together as will be later described to 70 form a flexible chain. These blocks or bars are preferably of similar design and shape and when thus joined together provide a continuity of design for the chain. At the end of the chain is provided an attaching device indicated generally at 11 for connection with the wrist watch.

Considering now more particularly the construction of the bars 10 of the chain, as best shown in Figure 5, they are provided 85 with upstanding side walls or flanges 12 so that when resting upon the wrist their external appearance is substantially that of a solid member. Also they are connected closely together, their end surfaces abutting. 90 This connection is preferably formed by means of links such as 13, over which are bent end flanges 14 of the bars. The bars of the chain being connected together in this manner, no gaps appear therebetween so 95 that the exterior appearance of the chain is substantially solid and uniform, regularly marked off by the lines appearing between adjacent bars.

The attaching device indicated at 11 in 100 Figure 1 has a hooked portion 15 by means of which connection is made with the wrist watch. This hooked portion 15 is formed upon a member 16 which is provided with upstanding side walls or flanges 17. A plate 105 member 18 is connected with these side walls 17 in a manner to be later described and thus spaced from the part 16 forms therewith, and the side walls 17, a hollow chamber or passage within the attaching device. 110

At the end of the chain formed by the bars 10 is a longer bar 19 which extends into this chamber or hollow portion of the attaching device. This longer bar 19 is, in 5 construction, similar to the bars 10, being connected to the adjoining bar 10 in the same manner in which the bars 10 are connected to each other and at its inner end within the hollow portion of the attaching 10 device is flanged as at 20. The rear end of the plate 18 is provided with a flange 21 and between this flange and the flange 20 is interposed a compression spring 22. The bar 19 is slideable longitudinally within the hollow 15 portion of the attaching device and the spring 22 thus forms a yielding connection therebetween urging the bar 19 inwardly. By pulling the bar 19 outwardly against the action of the spring 22, it is seen that 20 the chain is lengthened or extended longitudinally and that under the urge of the spring 22 the chain tends to contract to its normal length. Thus in the lengthening or 25 shortening of the chain the bar 19 simply moves outwardly or inwardly at the rear end of the attaching device. In this manner since the bar 19 thus telescopes within the attaching device, no gaps appear in the chain when it is extended. Preferably the 30 outer surface of the longer bar 19 is marked off to resemble in appearance a plurality of adjoining bars 10. In Figure 2 the chain is shown in extended position with the spring 22 compressed and it is seen that this 35 marking off of the surface of the bar 19 preserves the continuity of design formed in the chain by lines between adjoining bars 10. This is highly advantageous since the chain has substantially the same exterior 40 appearance in extended position as in normal position. The spring 22 is preferably made oval in cross section to best conform to the rectangular shape of the hollow portion of the attaching device in which it rests. 45 The forward end of the plate member 18 is provided with a pair of inwardly curved lugs 23 which are best shown in Figures 3 and 5. These lugs 23 pivotally support a member 24 which is adapted to swing into 50 and out of position to coat with the hook 15 and serve as a lock therefor. This member 24 is provided with a handle or lever 25 which, when the member 24 is in locking position, is in frictional engagement with 55 the outer surface of the side wall 17 of the attaching device. This frictional engagement of the lever 25 serves to dependably hold the lock in operative position. As is seen in Figure 5 the lugs 23 supporting 60 the lock 24 serve as a stop to limit the inner movement of the bar 19.

Considering now more particularly the material of which these parts are made, they are preferably made of metal which is filled 65 or plated with another more precious metal,

for example, they may be gold-filled or gold-plated. Referring particularly to Figure 6, the member 16 with its side walls 17 described above comprises preferably an inner layer of base metal 16^a having the side walls 17^a and an outer covering 16^b of a precious metal, such as gold. The plate member 18 comprises an inner member 18^a of base metal having an outer covering 18^b of gold. This plate member 18 rests upon the upper surface of the side walls 17^a of base metal of the member 16. The covering 16^b of gold extends beyond the ends of the flanges or side walls 17^a, as at 16^c and is flanged over the edges of the member 18. The covering 80 of precious metal 18^b terminates a short distance from the edges of the member 18^a upon which it is formed and the edges of the flanged portion 16^c of the covering 16^b meets these edges of the covering 18^b as at 26. 85 This line of meeting is clearly shown in Fig. 3. In this manner the flanged ends 16^c of the precious metal hold the member 18 in place and a complete covering of precious metal is provided. The surface of the member 18 forms the inner surface of the attaching device, that is, the surface which contacts the wrist, and it will be seen that the construction just described prevents any base metal from coming in contact with the 90 skin and further preserves the full thickness of the precious metal covering throughout and makes for most economical utilization of the precious metal employed.

Referring now particularly to Figure 8, 100 the bars 10 with their side walls or flanges 12 preferably comprise an inner member 10^a of base metal having the flanges 12^a, and an outer covering 10^b of precious metal. In forming the bars the base metal portion 10^a having flanges or side walls 12^a and the flanges 14 is preferably first formed as shown in Figure 8. Thereupon the outer coating 10^b of precious metal is applied. Then a part of the end portions of the 105 flanges 12^a is forced downwardly as shown in Figure 9, leaving a thinner portion 12^c of base metal and making the lower portion 12^d of the flanges thicker thus forming 110 shoulders 12^e. Thereupon the thin end portion 12^c of base metal, together with the covering of precious metal 10^b thereon is flanged or bent over against the shoulder 12^e. A cross section of the resulting structure 115 is shown in Figure 7 and it is seen that the flanged other portion 10^e of precious metal forms the inner surface of the bar, that is the surface which comes in contact with the skin. By forming this portion of the bars as above described the full thickness of the 120 precious metal at the points where it is flanged over is retained and the layer of precious metal is not strained or weakened in being bent over. Thus there is no danger 125 of cracking the thin layer of gold or other 130

precious metal to permit exposure of the base metal therebeneath. The inner surfaces of the side walls of the longer bar 19 are formed in a similar manner as shown 5 at 19° in Figure 6. Thus the surfaces of the chain and other parts which contact the wrist are all plated with the precious metal and the base metal which lends the necessary strength to the structure does not come 10 into contact with the skin. The precious metal employed is utilized in a most economical and advantageous manner.

From the foregoing it will be seen that there is herein provided a construction 15 which embodies the features of the invention and attains the objects thereof including many practical and useful advantages. It may here be noted that the terms "blocks" or "bars" as employed herein are to be interpreted broadly throughout to include any 20 suitable members adapted to perform the functions described.

As many possible embodiments may be made of the mechanical features of the 25 above invention and as many changes might be made in the embodiment above set forth, all without departing from the scope of the invention, it is to be understood that all matter herein set forth or shown in the 30 accompanying drawings is to be interpreted as illustrative and not in a limiting sense.

I claim as my invention:

1. In construction for wrist watch chains and the like, in combination, a plurality of 35 bars, and means connecting said bars to form a flexible chain of substantially continuous outer appearance, the connecting means between two successive bars being adapted to permit longitudinal extension of 40 said chain and said bars connected thereby having overlapping and relatively slidably portions arranged to conceal the gap occasioned by said extension.

2. In construction for wrist watch chains and the like, in combination, a plurality of 45 bars arranged end to end, means pivotally connecting certain of said bars at their adjacent ends to form a flexible chain of substantially unbroken outer appearance, and 50 means slidably connecting two other adjacent bars to permit longitudinal extension of said chain, said two bars having superposed portions arranged to conceal the gap occasioned by the extension of said chain.

3. In construction for wrist watch chains and the like, in combination, a plurality of 55 bars having exposed upper face portions, means connecting said bars with the upper face portions thereof in substantial alignment to form a flexible inexpansile chain of substantially continuous appearance, and a bar slidably connected with one of said bars and having an upper face portion of substantially the same width as that of the 60 upper face portion of said one bar and

overlapping the latter, thereby to maintain substantially continuous the appearance of said aligned upper face portions during elongation of the chain by slidable movement of said bar.

4. In construction for wrist watch chains and the like, in combination, a plurality of 70 bars, means connecting said bars to form a flexible chain of substantially continuous outer appearance, the connecting means between two successive bars being adapted to permit longitudinal extension of said chain and the bars connected thereby having overlapping and relatively slidable portions arranged to conceal the gap occasioned 75 by said extension of the chain, and a spring included in said last-mentioned connecting means between said two bars.

5. In construction for wrist watch chains and the like, in combination, a series of 80 successive link members having upper face portions and depending side portions, means pivotally connecting said link members with the upper face portions and the depending side portions thereof in substantial alignment to form a flexible inexpansile chain of substantially continuous appearance on 85 three sides thereof, another link member having an upper face portion and depending side portions, the latter being spaced to 90 receive therebetween one of said series of link members to form a continuation thereof, and connecting means between said last two link members arranged to permit relative 95 slidable movement of the one link member 100 within the other.

6. In construction for wrist watch chains and the like, in combination, a series of 105 successive link members having upper face portions and depending side portions, means pivotally connecting said link members with the upper face portions and the depending side portions thereof in substantial alignment to form a flexible chain of substantially continuous appearance on three sides 110 thereof, another link member having an upper face portion and depending side portions, the latter being spaced to receive therebetween one of said series of link members to form a continuation thereof, connecting means between said last two link members arranged to permit relative slid- 115 able movement of the one link member within the other, and a spring included in said last-mentioned connecting means urging 120 said one link member into the other.

7. In construction for wrist watch chains and the like, in combination, a series of 125 successive link members each having an upper exposed face and adapted to form a chain, the last link member thereof being extended in the direction of the length of the chain and formed into an attaching device, means pivotally connecting all of said link members but said last link member and 130

with the upper faces thereof in substantial alignment to form a flexible chain of substantially continuous outer appearance, and means slidably and yieldably connecting said last link member to its adjacent link member, the upper face of one overlapping the upper face of the other.

8. In construction for wrist watch chains and the like, in combination, a series of box-like link members, means connecting said link members to form a flexible chain of substantially continuous solid outer appearance, two successive box-like link members being dimensioned to be slidably received one within the other, and means limiting the slidable movement thereof in a direction away from each other, whereby said continuous appearance is maintained as said slidable movement takes place.

9. In construction for wrist watch chains and the like, in combination, a series of box-like link members, means connecting said link members to form a flexible chain of substantially continuous solid outer appearance, two successive box-like link members being dimensioned to be slidably received one within the other, and a spring interposed between said two slidable box-like link members and within the registering interiors thereof, said two slidable link members preventing disruption of said continuous appearance during extension of said chain thereby.

10. In construction for wrist watch chains and the like, in combination, a series of box-like link members connected together to form a chain of substantially continuous outer solid appearance, the end member of which is of greater length than the remaining members, a box-like link member dimensioned to receive slidably therein said elongated end link member, and a spring urging said end link member into said last mentioned link member.

11. In construction for wrist watch chains and the like, in combination, a series of box-like link members of substantially continuous outer solid appearance, the end member of which is of greater length than the remaining members, a box-like link member dimensioned to receive slidably therein said elongated end link member and having a portion thereof extended in the direction of the length of the chain, the extended portion being formed into an attaching device, and a spring urging said end link member into said last mentioned link member.

12. In construction for wrist watch chains and the like, in combination, means adapted to encircle the wrist, an attaching device shaped at one end thereof in the form of a hook and shaped at the other end thereof to receive slidably therein the end of said encircling means, a spring interposed

between said end of said encircling means and said device and urging the former into the latter, a projecting member associated with said device and positioned in the path of movement of said end of said wrist encircling means to limit the slidable movement therebetween, and a lock member supported from said projecting member and movable into operative relation to said hook.

13. The combination with wrist-encircling means, of an attaching device comprising a sheet metal member having a pair of depending side walls between which is slidably received the end portion of said wrist-encircling means, and a plate-like member attached to said walls and having an inwardly directed projecting member for limiting the slidable movement of said end portion of said wrist-encircling means relative to said attaching device.

14. The combination with wrist-encircling means provided with a projecting member at an end portion thereof, of an attaching device formed of sheet metal and provided with a pair of plate-like members held in spaced relation and between which said end portion of said wrist-encircling means with said projecting member thereon is slidably received, one of said plate-like members having two longitudinally spaced and inwardly directed lugs between which said projecting member on the end portion of said wrist-encircling means is slidably movable and thus with 100 said end portion is limited in its movement.

15. The combination with wrist-encircling means provided with a projecting member at an end portion thereof, of an attaching device formed of sheet metal and provided with a pair of plate-like members held in spaced relation and between which said end portion of said wrist-encircling means with said projecting member thereon is slidably received, one of said plate-like members having two longitudinally spaced and inwardly directed lugs between which said projecting member on the end portion of said wrist-encircling means is slidably movable and thus with 110 said end portion is limited in its movement, and a spring interposed between one of said lugs and said projecting member.

16. The combination with wrist-encircling means provided with a projecting member at an end portion thereof, of an attaching device formed of sheet metal and having a pair of depending side walls between which said end portion of said wrist-encircling means is slidably received, and a plate-like member secured to said side walls and having two longitudinally spaced and inwardly directed lugs thereon between which said projecting member on the end 120 125 130

portion of said wrist-encircling means is slidably movable and thus with said end portion is limited in its movement.

17. The combination with wrist-encircling means, of an attaching device comprising a sheet metal member having a pair of depending side walls, each of which is stepped to form a supporting ledge, and between which is slidably received the end portion 10 of said wrist-encircling means, and a plate-like member resting upon the supporting ledges of said walls and secured thereto and having an inwardly directed projecting member for limiting the slidable movement 15 of said end portion of the wrist-encircling means relative to said attaching device.

18. The combination with wrist-encircling means, of an attaching device comprising a sheet metal member having a pair of depending side walls, each of which is stepped to form a supporting ledge and an up-standing flange and between which side walls is slidably received the end portion 20 of said wrist-encircling means, a plate-like member resting upon the supporting ledges and having said flanges bent thereover to hold it in place, and an inwardly directed projecting member supported from said plate-like member for limiting the slidable 25 movement of the end portion of said wrist-encircling means relative to said attaching device.

19. The combination with wrist-encircling means, of an attaching device shaped at 30 one end thereof in the form of a hook and having a pair of depending side walls between which is slidably received the end portion of said wrist-encircling means, a plate-like member mounted upon said side 35 walls for substantially enclosing the end portion of said wrist-encircling means within said attaching device, a lock-member adapted to be moved into operative relation to said hook, and means mounting said lock member on said plate-like member.

20. In construction for wrist watch chains and the like, in combination, a plurality of bars, means connecting said bars to form an inexpansive chain, said bars forming a 50 continuity of design, an attaching device at the end of said chain, and means forming a connection between said chain and said attaching device adapted to permit longitudinal extension, said last mentioned means 55 having overlapping and relatively slidable parts of substantially the same width as that of said bars, adapted thereby to preserve said continuity of design of said chain up to said attaching device.

21. In construction for wrist watch chains and the like, in combination, a pair of members each having an upper face portion and depending side wall portions and adapted to form part of a chain, one of said members telescoping within the other and mov-

able relative thereto to permit longitudinal extension of said chain.

22. In construction for wrist watch chains and the like, in combination, a chain comprising a plurality of connected bars, an attaching device adjacent the end of said chain having a hollow part, a bar of greater length than said first bars forming part of said chain and extending within said hollow part and movable longitudinally therein, and a spring urging said last bar into said hollow part. 70

23. In construction for wrist watch chains and the like, in combination, a chain comprising a plurality of connected similar bars, an attaching device adjacent the end of said chain having a hollow part, a bar of greater length than said first bars, forming the end portion of said chain and having its surface marked to resemble a plurality of said first bars, said bar extending into said hollow part of said attaching device and being movable therein, and a spring within said hollow part yieldingingly urging said bar thereinto. 80

24. In construction for wrist watch chains and the like, in combination, means adapted to encircle the wrist, an attaching device connected thereto comprising a hooked member, and a lock member movable into operative relation to said hook and shaped to form therewith a closed loop and locked in position by friction with the surface of said attaching device. 90

25. In construction for wrist watch chains and the like, in combination, means adapted to encircle the wrist, an attaching device connected therewith comprising a hooked member, a member pivoted upon said attaching device adapted to swing into locking relation with said hook, and means connected to said member adapted to frictionally engage a portion of said attaching device to secure said member in locking position. 100

26. In construction for wrist watch chains and the like, in combination, means adapted to encircle the wrist, an attaching device adjacent the end thereof comprising a member having a hooked portion, a second member spaced from said first member and secured thereto forming a recess therebetween, and means connected to said wrist encircling means, extending lengthwise into said recess and yieldingingly connected therein to said attaching device. 110

27. In construction for wrist watch chains and the like, in combination, means adapted to encircle the wrist, an attaching device adjacent the end thereof comprising a member having a hooked portion, a second member spaced from said first member and secured thereto forming a recess therebetween, means connected to said wrist encircling means, extending into said recess and yield- 120

ingly connected therein to said attaching device, and a member mounted upon said second member adapted to move into locking position with respect to said hook and 5 secured in position by friction.

28. The combination with wrist-encircling means having two longitudinally spaced projecting members at the end portion thereof, of an attaching device formed of 10 sheet metal and provided with a pair of plate-like members held in spaced relation and between which the end portion of said encircling means with at least one of said projecting members is slidably received, one 15 of said plate-like members having an inwardly directed projecting member with which either of said two longitudinally spaced projecting members may co-act to limit the slidable movement of said end 20 portion of the wrist-encircling means relative to said attaching device.

29. The combination with wrist-encircling means, of an attaching device formed of sheet metal and having a pair of depending side walls between which is slidably received the end portion of said wrist-encircling means to permit an elongation thereof, and said device being formed at its end into a hook, a plate-like member supported by said side walls to substantially enclose the end portion of said wrist-encircling means between said side walls, and locking means forming substantially an extension of said plate-like member in a direction toward said hook but movable 30 relative thereto to form with the hook a closed loop. 25

In testimony whereof, I have signed my name to this specification this tenth day of December A. D. 1923.

AXEL PERSON.
